UNITED STATES PATENT OFFICE

1,990,125

FUEL PUMP SHIELD

Roy H. Kentfield, Gillespie, Ill.

Application April 3, 1934, Serial No. 718,860

1 Claim. (Cl. 103—205)

This invention appertains to new and useful improvements in fuel pumps, the principal object being to provide a shield for conventional pumps to prevent vapor from the crank case reaching the movable parts of the pump and causing them to corrode and stick.

During the course of the following specification, other important objects and advantages of the invention will become apparent to the reader.

10 In the drawings:—

Figure 1 represents a side elevational view of the pump, with the shield installed thereon.

Figure 2 represents a fragmentary longitudinal sectional view through a pump and crank case.

15 Figure 3 represents a cross sectional view taken substantially on line 3—3 of Figure 2.

Figure 4 represents a side elevational view of the shield guide.

Figure 5 represents an end elevational view of 20 the guide.

Figure 6 represents a perspective view of the shield plug.

Referring to the drawings wherein like numerals designate like parts, it can be seen in 25 Figures 1 and 2, that numeral 5 represents the usual crank case and numeral 6 represents the usual pump shaft having the eccentric circumferentially disposed groove 7 therein.

Numeral 8 represents the usual shell portion 30 of the valve having the inlet 9 and the outlet 10, the same being connected to the neck 11 which is flanged, as at 12, and secured by screws 13 to the crank case 5.

Interposed between the flange 12 and the crank 35 case 5 is the circumferentially extending flange

14' of the guide 14, which is of tubular construction and extends into the crank case. Numeral 15 represents the movable cylinder of the pump around which the usual spring 16 is convoluted, with one end bearing against a circumferentially extending flange on the inner end of the cylinder 15.

Numeral 18 represents the push rod which is slidably disposed snugly through an opening 19 in the resilient plug 20 which forms a shield and snugly fits within the inner end of the guide 14, as in the manner clearly shown in Figure 2.

Thus no oil can get to the pump parts as this plug 20 will exclude all vapors from entering the 15 pump.

While the foregoing specification sets forth the invention in specific terms, it is to be understood that numerous changes in the shape, size and materials may be resorted to without departing from the spirit and scope of the invention 20 as claimed hereinafter.

Having thus described the invention, what is claimed as new is:—

An attachment for a fuel pump wherein the fuel pump is of the type extending into the crank 25 case and secured to the crank case by a flange and bolts; a tubular shield for disposition into the crank case and provided with packing means at its inner end through which the usual pump push rod can snugly operate, and a flange at the 30 outer end of the shield for supporting the shield, said flange of the shield being interposed between the securing flange of the pump and the crank case.

ROY H. KENTFIELD. 35
